ELECTRODEPOSITION ANODE

Leslie N. Smith, Cleveland Heights, Ohio, assignor to The Harshaw Chemical Company, Cleveland, Ohio, a corporation of Ohio

Application September 10, 1945, Serial No. 615,462

4 Claims. (Cl. 204—290)

1

This invention relates to electrodeposition anodes and more specifically to anodes of the type which are built up from sheets of the metal to be deposited such as nickel electrosheet.

Prior to my invention it has been suggested to use nickel electrosheet, without melting, as a source of nickel for the electrodeposition of that metal but, so far as I am aware, no fully satisfactory method has been suggested for supporting the electrosheet in the electroplating tank. It has been suggested (U. S. Patent No. 1,596,030) to stamp the nickel electrosheet into the form of washers which are then supported by means of a bolt passing through a considerable number of them and bent over to form a supporting hook. This involves considerable fabrication cost and eventually permits fragments to fall into the tank. It has been suggested also to support small pieces of nickel electrosheet in perforated metallic baskets. This is feasible but the contact between the various pieces and the source of current is imperfect and consequently this type of anode has met with only a limited acceptance.

The object of my invention is to provide improved electrodeposition anodes of the type indicated, overcoming to a considerable extent the difficulties mentioned and approaching as nearly as possible a situation in which the user would handle the electrosheet anodes in the same way that he would handle the conventional cast or rolled anodes.

Still further objects of the invention are to minimize the cost of manufacturing the anode, to achieve simplicity in construction and to reduce the number of manufacturing operations to a minimum.

With the foregoing and other objects in view the invention consists in the novel features hereinafter described and illustrated in the accompanying drawings wherein Fig. 1 is an elevation of a composite anode according to the invention; Fig. 2 is a side view of the same; Fig. 3 is a transverse section, double size, corresponding to the line 3—3 of Fig. 1; Fig. 4 is a greatly enlarged fragmentary section showing a modified form of connector for affording electrical and mechanical connection between the various strips of electrosheet; Fig. 5 is a side elevation of a further modification of the invention; Fig. 6 is a front view showing a plurality of the anode pieces shown in side view of Fig. 5; Fig. 7 is a further modified form similar to the form shown in Figs. 5 and 6 but providing for the possibility of greater anode length than obtainable in single pieces; Fig. 8 is a side view of the composite anode shown in

2

Fig. 7; Fig. 9 is a front view of a further modified form made up of pieces similar to those shown in Fig. 5 but suspended from the bus bar by an extension permitting the anode to be lowered where the distance between the bus bar and the solution level is too great for the type shown in Fig. 5; Fig. 10 is a side view of the form shown in Fig. 9; Fig. 11 is a front view of another form of the invention; Fig. 12 is a side view of the form shown in Fig. 11; Fig. 13 is a front view of a modification similar to that shown in Fig. 11 but omitting some features thereof; Fig. 14 is a side view of the form shown in Fig. 13; Fig. 15 is a front view of a still further modified form and Fig. 16 is a side view of the form shown in Fig. 15.

Referring now to the drawings, the numeral 10 indicates generally a composite anode composed of three elongated strips 11 of nickel electrosheet all of which are of identical rectangular cross section and a strip 12 provided with a tapered portion 13 and a narrow portion 14. The electrosheet is available in sheets up to about 3 feet in greatest dimension and lends itself to being cut into strips of various widths as desired and various lengths not exceeding the maximum available. In the modification of Figs. 1 to 3 I have indicated an anode constructed from strips of electrosheet which may be about 36 in. in length, 4 in. in width. The strip 12 is provided with the narrow portion 14 which may be 1 in. in width and may be bent over as indicated by dotted lines in Fig. 1 to form a hook adapted to engage a current carrying a bar 15.

The strips 11 and 12 may be secured together by a narrow band of adhesive material as indicated at 16. The adhesive material should be inert to the electroplating solution and may be composed of rubber strips cemented or vulcanized to the strips 11 and 12 or it may be simply strips of rubber cement applied to the surfaces as the laminated structure is being built up. Other adhesives may be used provided they are insoluble in and inert to the electroplating solution in which the anode is to be used. Various types of synthetic resin adhesives meet these requirements. It is desirable that the adhesive strips 16 be relatively narrow so that the portions of the anode strips between the adhesive strips may corrode almost if not quite entirely away before corrosion is too greatly reduced by the masking effect of the then projecting adhesive. I have shown these strips as being a little more than an inch in width. In some cases it may be desirable that they be narrower than shown for example $\frac{1}{2}$ or $\frac{3}{4}$ of an inch in width. The adhesive strips serve to hold the

anode strips together and if when the anode is largely consumed one of the anode strips should have corroded entirely through the adhesive strips will frequently prevent fragments from falling into the tank. In Figs. 1 and 2 I have shown metallic strips 17 welded at the upper ends to the anode strips so as to provide electrical contact between the four anode strips. Current will then flow from the bus bar 15 through the hook 14 to the connecting strips 17 and thence to the anode strips 11. It will be understood that the thickness of the adhesive strips 16 is exaggerated in Fig. 3 whereas for convenience these strips are not shown at all in Figs. 1 and 2.

In Fig. 4 I have shown an alternative method of connecting the anode strips together. This involves punching a hole 18 through each of the anode strips 11 and 12. A bolt 19 is passed through the hole 18 and annular elements 20 and 21 are provided for affording electrical contacts between the anode strips 11 and 12. The elements 20 may be placed between the anode strips as the laminated structure is being built up and the bolt 19 may then be passed therethrough for holding the anode strips in firm contact with the elements 20. Rubber washers 22 and 23 may be interposed between the nut 24 and the anode strip 11 on the one end and the bolt head 25 and the anode strip 11 on the other end. The bolt 19 and nut 24 may be composed of non-metallic material or relatively insoluble nickel or it may be composed of any metal if the bolt head and the nut are provided with an insoluble coating.

In Figs. 5 and 6 I have shown a very simple arrangement for utilizing nickel electrosheet in the form of long strips. In this form the anode strips 26 are provided with supporting hooks by the simple expedient of stamping or otherwise forming an angularly upwardly extending notch 27 in one edge of the strip adjacent to one end thereof. These notches may extend at any suitable angle and should be of a width suitable for receiving the bus bar 28 which is to supply current. These anode strips may be hung on the bus bars which extend along the sides of the usual plating tanks at whatever intervals the plater may consider necessary to give the desired anode area. In Fig. 6 I have shown four such anodes and it is to be understood that they may be uniformly spaced along the bus bars or grouped together in groups having little or no space between the anodes of each group. When the anode strips have been corroded away until they become too short for further use, the fragments may be placed in a basket in accordance with usual practice and thus completely consumed.

In some cases it may be desirable to have a longer anode than can be obtained by the use of single strips such as shown in Figs. 5 and 6. In Figs. 7 and 8 I have shown a modified form similar to that shown in Figs. 5 and 6 but affording greater anode length. This greater length is secured at the expense of another operation in the formation of the anode strips involving punching or otherwise forming holes in the strips. In this form of the invention, the anode strip 29 is provided with an angularly, upwardly extending notch 30 similar to the notch 27 in the anode strip 26 and is also provided with a hole 31 which may be punched or drilled therethrough for the purpose of receiving a pin 32. Anode strips 33 may have similar holes 34 punched or drilled therethrough adjacent the upper end and

which also receives the pin 32. The pin 32 may be a tight fit or a loose fit as desired and when the anode strips have been assembled with the pin 32 in position as shown, a rubber band or

5 the like 35 is placed over the assembly to hold the pin in place and shield it from the dissolving action of the current. It will be noted that the upper end of the anode strip 29 projects above the upper ends of the anode strips 33. The 10 amount of such projection may be adjusted in accordance with the distance from the bus bar 36 to the normal level of plating solution in the tank so that the strips 33 may be entirely submerged.

15 The anode strips 33 are also provided with holes 37 near the lower ends thereof which are adapted to receive a pin 38. The pin 38 also passes through a hole 39 in the upper end of an anode strip 40. The pin 39 is shielded from the action 20 of the current by means of a rubber band or the like 41. The anode strip 40 is provided with another hole 42 at a lower point which is adapted to receive a pin 43 which also passes through holes 44 in anode strips 45. The pin 43 is shielded by 25 a rubber band or the like 46. It will thus be seen that composite anodes of any length can be built up in very simple fashion using simply strips of electrosheet with notches and holes formed therein and with no accessories beyond the connecting pins and rubber bands which obviously can be obtained very cheaply. The pins 32, 38 and 43 preferably are made by cutting off lengths of nickel rod so that under no circumstances need they result in the introduction of any foreign 30 metal into the plating solution.

In Figs. 9 and 10 I have shown a modification similar to that shown in Figs. 5 and 6 wherein provision is made for lowering a group of anode strips with respect to the supporting bus bar.

40 This will be found useful in connection with tanks having the normal solution level at a substantial distance below the bus bar. In this form, the anode strips 47 are similar to the strips 26 shown in Fig. 5, being provided with a notch 48 adapted to receive a U-shaped supporting member 49 provided with hooks 50 at its ends. I have shown the notches 48 extending at a flatter angle than in the modified forms but it is to be understood that the angle is a matter of choice in either 50 case, the essential being that it extend upwardly at an angle sufficient to avoid unintentional disengagement of the anode strip from the support. The hooks 50 are received on the usual bus bar 51. The anode strips 47 may if desired be held 55 in contact with each other by means of rubber bands 52 and 53. These are not strictly necessary and may be omitted or only a single one thereof may be used.

In Figs. 11 and 12 I have shown a modified form 60 of the invention somewhat similar to that shown in Fig. 1. In this form, a laminated anode structure is built up from strips of nickel electrosheet. Each layer of the laminated, composite anode structure may be made up of only a single strip

65 of nickel electrosheet or a plurality thereof arranged end to end as shown. In either case, the strips are secured together by means of an adhesive strip which is narrow relative to the width of the anode strip similar to the construction indicated in Fig. 3. This can best be seen in Fig. 12. In the event more than one anode strip is used in any layer of the laminated composite anode, the adhesive strip is interrupted near the joint between the two strips and a piece of metal

70 indicated in Fig. 12. In the event more than one anode strip is used in any layer of the laminated composite anode, the adhesive strip is interrupted near the joint between the two strips and a piece of metal 75 of approximately the same thickness as the adhe-

sive strip is substituted for the adhesive strip to bridge the gap and form an electrical connection between the two anode strips. These metallic connectors are held in contact by the adhesive. In Figs. 11 and 12 the numeral 54 indicates the various anode strips, the numeral 55 indicates the various adhesive strips and the numeral 56 indicates the various metallic connectors bridging the gap between the anode strips. At the upper end there are metallic strips 57 electrically connecting the anode strips which they contact. Between the two inner anode strips I prefer to drill and tap an opening adapted to receive the threaded lower end of an anode hook 58 which is adapted to engage a bus bar 59 to support the composite anode.

In order to strengthen the construction I prefer to place a metal band around the upper ends of the uppermost anode strips and to taper the threaded portion 61 of the anode hook so that as the tapered thread is screwed into place it will push the anode strips at either side outwardly against the band 60 and grip the strips 57 firmly between the anode strips to form a secure electrical and mechanical connection. It is to be understood that the band 60 may be omitted if the thread 61 is not tapered and the adhesive strips can be relied upon to hold the laminated structure together and to hold the plates 56 and 57 in electrical contact with the anode strips. It is to be understood also that a satisfactory laminated anode of this type can be made using only one anode strip in each layer. Such structure would be the result if the composite anode of Fig. 11 should be cut off above the uppermost connector 56.

In Figs. 13 and 14 I have shown a modification similar to that shown in Fig. 11 but omitting the adhesive strips altogether and employing only a single anode strip in each layer. In this case I have shown four anode strips, two outer strips 62 and two inner strips 63. At the upper end between the inner strips 63 there is tapped and drilled a tapered opening adapted to receive a tapered thread 64 on an anode hook 65 which is adapted to engage the bus bar 68. Surrounding the upper ends of the four anode strips is a band 66. When the tapered thread on the anode hook 65 is screwed into place, it causes the two inner anode strips 63 to separate as shown in exaggerated fashion at 67. This causes the anode strips to be urged outwardly into firm contact with the band 66 and thereby locks the parts of the structure in the relative positions indicated. I have shown the band 66 as being made from a rod of circular cross section whereas the band 60 is shown as being made of a ribbon of rectangular cross section. It is to be understood that these are equivalent and interchangeable in either modification. The resulting composite anode can be handled in the same way as ordinary cast anodes and its manufacture involves similar operations in respect to the attachment of the anode hook 65.

In Figs. 15 and 16 I have shown a modified form of the invention quite similar to the form shown in Fig. 11 but involving an uneven number of layers of anode strips. In this case, the anode strip 69 is drilled and tapped at its upper end to receive the threaded lower end 70 of an anode hook 71 which is adapted to support the composite anode on a bus bar 72. At each side of the anode strip 69 is a connecting strip 73 adapted to form electrical connections with the outer anode strips 74. The anode strip 75 is connected

to the anode strips 69 by a bridging metallic strip 76. These various anode strips and connectors are held together by the adhesive strips 77 in the same manner as shown and described in connection with Fig. 11. In this as in previous modifications the adhesive strips are narrower than the anode strips so as to avoid undue shielding action toward the end of the life of the anodes.

10 While I have shown and described several illustrative embodiments of my invention I wish it understood that other variations may be made within the scope of my invention and I desire to be limited only in accordance with the appended claims and the prior art.

15 Having thus described my invention, what I claim is:

20 1. A laminated, soluble, electrodeposition anode, suitable for use in an electroplating bath, comprising a plurality of elongated strips of electrolytic metal sheet, each of a length less than the length of the anode, said strips being arranged in layers with the joints staggered, elongated strips of non-metallic, non-conductive material interposed between and adherent to strips in adjacent layers and mechanically connecting the same together, said non-conductive strips terminating short of each joint and a sheet metal bridge interposed between the metal strips in 25 bridging relation to two strips in the same layer and electrically connecting the same, and metallic supporting means electrically connected to at least one of said strips for supporting the entire anode, said non-conductive strips being inert to 30 and insoluble in said bath.

2. A laminated, soluble, electrodeposition anode, suitable for use in an electroplating bath, comprising a plurality of elongated strips of electrolytic metal sheet, each of a length less than the length of the anode, said strips being arranged in layers with the joints staggered, elongated strips of non-metallic, non-conductive material interposed between and adherent to strips in adjacent layers and mechanically connecting the same together, said non-conductive strips terminating short of each joint and a sheet metal bridge interposed between the metal strips in 40 bridging relation to two strips in the same layer and electrically connecting the same, and metallic supporting means electrically connected to at least one of said strips for supporting the entire anode, said non-conductive strips being inert to 45 and insoluble in said bath and of a width less than the width of said strips of electrolytic metal sheet whereby to avoid interference with solution of said strips of electrolytic sheet by said non-conductive strips until a major portion of the former has been dissolved.

3. A laminated, soluble, electrodeposition anode, suitable for use in an electroplating bath, comprising a plurality of layers, two of said layers including each an elongated strip of electrolytic metal sheet, and another layer interposed between said layers and including non-metallic, 55 non-conductive material and metallic, conductive material, said non-metallic material being adherent to adjacent strips of electrolytic metal sheet and mechanically connecting the same together and said metallic material being non-adherent to and interposed between and electrically connecting said strips of electrolytic metal sheet and being held in electrical contact therewith by said non-conductive material, and metallic supporting means electrically connected to at least 60 one of said strips of electrolytic metal sheet for 70

supporting the entire anode, said non-conductive strip being inert to and insoluble in said bath.

4. A laminated, soluble, electrodeposition anode, suitable for use in an electroplating bath, comprising a plurality of layers, two of said layers including each an elongated strip of electrolytic metal sheet, and another layer interposed between said layers and including non-metallic, non-conductive material and metallic, conductive material, said non-metallic material being adherent to adjacent strips of electrolytic metal sheet and mechanically connecting the same together and said metallic material being non-adherent to and interposed between and electrically connecting said strips of electrolytic metal sheet and metallic supporting means electrically connected to at least one of said strips of electrolytic metal sheet for supporting the entire anode, said non-conductive material being in the form of an elongated strip extending longitudinally of said strips of electrolytic metal sheet, being inert to and insoluble in said bath and being of a width less than the width of said strips of electrolytic metal sheet whereby to avoid interference with solution of said strips of electro-

lytic sheet by said non-conductive strip until a major portion of the former has been dissolved.
